To all whom it may concern:

Be it known that I, Vallejo Gantner, a citizen of the United States, residing at Hollywood, county of Los Angeles, State of California, have invented a new, original, and ornamental Design for a Textile Fabric, of which the following is a specification, reference being had to the accompanying drawing, forming part thereof,

The figure of the drawing is a face view of a textile fabric embodying my design.

I claim:

The ornamental design for a textile fabric, substantially as shown.
